DESIGN FOR A COMBINATION VANITY MIRROR AND CASE

William Lyons, Lynbrook, N. Y., assignor to William Lyons Novelty Co., New York, N. Y., a copartnership

Application May 7, 1942, Serial No. 106,810

Term of patent 3½ years

To all whom it may concern:

Be it known that I, William Lyons, a citizen of the United States, resident of Lynbrook, in the county of Nassau, State of New York, have invented a new, original, and ornamental Design for a Combination Vanity Mirror and Case, of which the following is a specification, reference being had to the accompanying drawing, forming part thereof.

I claim:

The ornamental design for a combination vanity mirror and case, substantially as shown.

WILLIAM LYONS.
